UNITED STATES PATENT OFFICE.

CHARLES G. GADDIS, OF OLNEY, ILLINOIS.

SAFETY APPLIANCE FOR OIL-TANKS.

1,019,779.

Specification of Letters Patent. Patented Mar. 12, 1912.

Application filed March 16, 1911. Serial No. 614,925.

To all whom it may concern:

Be it known that I, CHARLES G. GADDIS, a citizen of the United States of America, residing at Olney, in the county of Richland and State of Illinois, have invented certain new and useful Improvements in Safety Appliances for Oil-Tanks, of which the following is a specification.

This invention relates to certain new and useful improvements in safety devices for tanks, particularly oil tanks, and has for its object to provide a device of this kind that will in case of fire automatically release the oil in a tank and convey it away to a place of safety; one that may be readily applied to any tank and one that is simple in construction and cheap to manufacture.

To these ends the invention consists in the novel details of construction and combination of parts more fully hereinafter described and particularly pointed out in the claims.

Referring to the drawings forming a part of this specification in which like numerals designate like parts in all the views:—Figure 1 is a side elevation of an oil tank showing my invention applied thereto, parts being broken away for clearness. Fig. 2, is an enlarged cross section on the line 2—2 of Fig. 1. Fig. 3 is a longitudinal section on line 3—3 of Fig. 2. Fig. 4 is an enlarged detail sectional view showing the manner of joining the strip of fusible metal and the shield to the tank. Fig. 5 is a detail view showing a modified form of lever; and, Fig. 6 is a detail view showing a modified form of fastening a strip of fusible metal to a tank.

1 indicates an oil tank of any well known form of construction formed of sections 2 between which is held by bolts 3 a strip of fusible metal 4. This strip of fusible metal extends the entire length of the side of the tank and is joined to the bottom thereof by bolts 5, see Fig. 3.

To strengthen the joint at the union of the fusible metal and the tank and to prevent any leakage of the oil at that point, strips 6 are held against the sides of the fusible strip on the inside of the tank, by the bolts 3.

Mounted on the outside of the tank and covering the fusible metal strip 4 is a safety guard or shield 7, provided with flanges 8 and held by the bolts 3 and 9 to the sides thereof. This shield communicates at the bottom of the tank with a conduit 10. 11

indicates cross rods mounted within the shield 7 and extending from side to side for strengthening the same.

A series of angle irons 12, held on the inside of the tank 1 by bolts 13, are adapted to reinforce the same, where the fusible metal is located. These angle irons are so formed that they may not interfere with the removal and insertion of new fusible metal when desired, see Fig. 2.

Located at or near the bottom of the safety shield 7 is an auxiliary safety device comprising a lever 14 adapted to travel in a slot 14' in the front of the shield, said lever being fulcrumed within the shield as shown at 15 between the bearing plates 16 held by rivets 17 to the front of the shield and is provided with a hooked end 19 having an upper cutting edge 20 and a lower cutting edge 21, which edges are adapted to destroy the fusible metal strip 4 when the lever is operated. 22 indicates a shutter surrounding the lever 14 and held between the lugs 23 on the bearing plates 16. This shutter is adapted to travel up and down with the lever and keep the slot 14' closed at all times to prevent the escape of oil therethrough when the device is in operation.

In the modification shown in Fig. 5 the lever is shown provided with a series of hooked ends 24 all of which are provided with cutting edges 25. The shutter 23 in this case is held between guides 26 riveted to the front of the safety shield 7. This lever may be adjusted to the position as shown in dotted lines in Fig. 3 so that it may be operated by a direct upward pull instead of a downward pull as shown.

In the modification as shown in Fig. 6 the fusible strip 4 is shown closing a smaller opening 27 in the side of the tank. These fusible strips may be of any appropriate width and length according to the size and capacity of the tank and may be distributed around the tank if desired. They are to be made of lead or any other metal that will fuse at a temperature not to exceed 590° and applied to tanks that hold oil of any kind.

In case of a fire the heat will cause the metal strip to fuse and release the oil in the tank which will flow into the safety shield 7 and down into the conduit 10 where it will be conveyed to a place of safety.

By the operation of the lever 14 of the auxiliary device the fuse may be destroyed

near the lever and oil may be released and flow to a place of safety as above described.

By the use of a device of this kind it may readily be seen that the danger of oil tanks catching on fire and exploding and the loss of great quantities of oil may be eliminated.

It is not to be understood that I limit myself to the details of construction and arrangements of parts herein described and illustrated, as it is manifest that variations and modifications may be made in the features of construction and arrangement in the adaptation of the device to various conditions of use without departing from the spirit and scope of my invention and improvements. I therefore reserve the right to all such variations and modifications as properly fall within the scope of my invention and the terms of the following claims.

What I claim is:

1. The combination with a tank formed of sections adapted to hold oil; of a safety device applied thereto comprising a strip of fusible metal connecting said sections, and a shield mounted on said tank spanning said strip and providing a conduit for the purpose set forth.

2. The combination with a tank adapted to hold a supply of liquid, of a safety device therefor comprising a strip of fusible metal

mounted on said tank; a conduit and a means surrounding said fusible metal adapted to convey the liquid to said conduit when said fusible metal is destroyed, as set forth. 35

3. The combination with a tank formed of sections, of a safety device applied thereto comprising; a shield mounted on the side of said tank and connecting said sections, a strip of fusible metal connecting said sections within said shield; reinforcing bars within said tank connecting said sections, and a means mounted on said shield adapted to destroy said fusible metal for the purpose set forth. 40 45

4. The combination with a tank formed of sections, of a safety device applied thereto comprising; a shield mounted on the side of said tank and connecting said sections, a strip of fusible metal connecting said sections within said shield; reinforcing bars within said tank connecting said sections; and a lever mounted on said shield and provided with a cutting edge adapted to destroy said fusible metal for the purpose set forth. 50 55

In testimony whereof I affix my signature in presence of two witnesses.

CHARLES G. GADDIS.
